F. E. HOBSON ET AL

FUEL DISTILLING APPARATUS

Filed April 6, 1925

Patented June 5, 1928.

1,672,860

UNITED STATES PATENT OFFICE.

FRANK E. HOBSON AND JAMES F. SHELTON, OF BELLINGHAM, WASHINGTON; SAID HOBSON ASSIGNOR TO SAID SHELTON.

FUEL-DISTILLING APPARATUS.

Application filed April 6, 1925. Serial No. 20,932.

Our invention relates to improvements in fuel distilling apparatus wherein sawdust, or other comminuted wood; slack coal, or other comminuted coal; comminuted peat, and the like, are carbonized, and the products of the destructive distillation of said materials including charcoal, are saved.

This invention is an improvement on the invention disclosed in the application for Letters Patent for fuel distilling apparatus by said Frank E. Hobson, filed Nov. 26, 1923, Serial No. 676,953 which has for its principal object the production of a retort through which comminuted fuel is caused to move under positive control while under conditions adapted to extract and save the products of destructive distillation.

One of the objects of our improvement is to introduce heat-conducting and heat-distributing means between the heated wall of the retort and the material therein which conduct heat from said wall to said material while preventing contact between the wall and material, and another object of our improvement is to compel downward movement of said material nearest said hot wall.

We attain these objects with the mechanism illustrated in the accompanying sheet of drawings in which Figure 1 is a front elevation of our retort in section on a medial, vertical plane, Fig. 2 is a top plan view downward from the line 2-2, and Fig. 3 is a plan view downward in section on the line 3-3.

Similar characters refer to similar parts throughout.

More particularly: The outside shell 4 of our retort is cylindrical and its lower end bears on the bottom external flange 5 of the inner wall 12 of the retort, while said flange bears on foundation 6. In wall 4 near its lower end is annular enlargement 7 into which enters the flue, or smoke pipe 8 of furnace a^8 having damper 9. The upper end of the heat chamber a^4 between walls 4 and 12 is closed at b^4 and from said chamber at its upper end leads smoke pipe 10 having damper 11 and being connected to a stack not shown. Inner wall 12 of the retort extends from its lower flange 5 to receiving hopper 18, but has annular enlargements 14 and 16 near its upper end. In heat chamber a^4 is helical baffle 13 which compels the hot gases of combustion from furnace

a^8 to pass several times around said chamber while passing from said furnace to smoke pipe 10. Pipe 15 is connected to enlargement chamber 14 and pipe 17. The latter pipe leads from enlargement chamber 16 to a gas condenser not shown. Receiving hopper 18 is connected to the upper end of inner wall 12 and is supported on and fastened to beams 19, 19. Chute 20 connects receiving hopper 18 with a source of material not shown. Hopper 18 discharges into retort chamber a^{12} through opening a^{18} which is circular, concentric with wall 12 and somewhat smaller than the upper end of said wall where it joins hopper 18.

A plurality of concentric, superposed, inverted, truncated hollow cones 21 are fastened together to form an annular louvered curtain by bars 22. This curtain loosely fits the inside of wall 12 and extends upward from near the bottom of the retort chamber to closely beneath hopper 18, and the external diameter of the upper member 21 is larger than hopper outlet a^{18} . Bars 22 extend above louvered curtain 21 and are fastened to hoop 23. A plurality of concentric, superposed, truncated hollow cones 24 are fastened together with four bars 25 attached to the inner rim of each of the cones. This latter set of truncated hollow cones is centrally placed in the retort and extends from the upper end of gas pipe 26 below to the lower end of gas pipe 27 above. Below, bars 25 extend beyond the lowest cone and engage the upper end of pipe 26 which serves as a guide therefor. Above, bars 25 extend beyond the conical part to the top of neck b^{24} of highest cone 24 and are fastened to the inner end of gas pipe 27 with which said neck makes a closure. Truncated cones 24 with their frame bars 25 constitute a louvered gas receiver, or collector. Gas pipe 27 is mounted for vertical shifting in guides 28 which are fastened within collar 29. Collar 29 is fastened by brackets 30 and standards 31 to receiving hopper 18. A short rubber hose 32 makes a flexible connection between the outer end of gas pipe 27 and, the continuation thereof, pipe 33 which is connected to a gas condenser not shown. To the elbow of pipe 27 in the axis of its vertical end is fastened eye stud 34. To eye 34 is fastened the lower end of cable 35 which is reeved over lead

sheave 36 and fastened to the upper end of fulcrumed lever 39. Sheave 36 is mounted for revolution in a bearing bracket fastened to beam 37. In a hole 38 in the upper end 5 of fulcrumed lever 39 cable 35 is fastened, as stated. Lever 39 is fulcrumed at 40 to a bracket fastened to beam 41. The lower end of cable 42 is fastened to hoop 23 and reeved over lead sheave 43 and its upper 10 end is fastened in hole 46 in lever 39 below its fulcrum. At the opposite end of a diameter from the fastening point of cable 42 cable 44 is fastened to hoop 23, is reeved over lead sheave 45 and has its upper end 15 fastened in hole 46 with cable 42. Sheaves 43 and 45 are mounted in bearing brackets for revolution which are fastened to beam 37. As illustrated, eight spaced chains 47 are pendant in the retort chamber a^{12} between louvered curtain 21 and louvered gas collector 24. Their lower ends approach the lower end of the retort chamber and their upper ends are fastened to hoop 48. At the opposite ends of a diameter of hoop 25 48 are fastened the lower ends of cables 49 and 51 which are reeved over lead sheaves 50 and 52 respectively, and their upper ends join at hole 53 in the lower end of lever 39 in which they are fastened. A cable 54 is 30 connected between the lower end of lever 39 and a pin a^{55} in crank 55. Crank 55 is fastened to one end of shaft 56 which is mounted for revolution in a bearing bracket fastened to beam 57. On shaft 56 is also 35 fastened power pulley 58 on which is mounted belt 59 connected to a course of driving power not shown. The oscillation of lever 39 on fulcrum 40 in the direction of sheaves 50 and 52 is limited by stop screw 60 engaged in a bracket 61 fastened to beam 41. The bottom 62 of the retort is hopper form and across its bottom plate are drawn a 40 gang of conveyor chains, one of which is shown at 63, mounted over sprocket wheels 64 and a^{64} , the latter of which is driven by pulley 65 connected to a power pulley, not shown, by belt a^{65} . Material drawn from hopper 62 by chains 63 fall into chute 66 which conducts it to the desired container, 45 not shown.

As illustrated, pipe 27 with louvered gas collector 24 attached, is adapted for vertical shifting, as also are louvered curtain 21 and chains 47. The louvered curtain and 50 gas collector are set against each other through their connections with lever 39 while the weight of chains 47 is added to that of the louvered curtain with an advantage in lever length. Thus the weight of 55 the three movable parts of the retort operate to force lever 39 against stop 60. The length of cable 54 is suited to retain lever 39 in its full-line position when crank 55 is in its full-line position, and when said crank is in its dotted position at 55' lever 39 is against stop

60 at 39' and cable 54 is slack and in its dotted position at 54'. Hence slow revolution of crank 55 causes louvered curtain 21 and louvered gas collector 24 to slowly rise and fall, oppositely, through a small distance between longer periods of pause while simultaneously and similarly chains 47 are vertically shifted with the louvered curtain but through about three times the space. In practice by preference the distance through 75 which the louvered curtain and the louvered gas collector are reciprocated is about one-half inch while the chains move about one and one-half inches. As stated, these movements are made slowly with longer periods 80 of pause intervening.

The presence of the louvered curtain 24 next to the inside of the inner shell 12 prevents material within the retort chamber a^{12} from coming in contact with said wall 85 during the entire extent of said curtain. As illustrated, this curtain extends from immediately beneath hopper outlet a^{18} to a point below enlargement 7, into which the hot gases of combustion from furnace a^8 enter on their way through chamber a^4 to smoke pipe 10. Therefore, there is relatively little heat delivered to the material within the retort which is below the lower end of curtain 24. Heat from shell 12 must cross 90 a short space of air by convection and radiation to reach the material exposed between the louvers of said curtain and in addition must pass through these louvers by conduction to enter the material lying on the inner sloping surface of said louvers. In this way 95 heat from shell 12 is distributed and modified before entering into said material; thus diminishing the danger of said material being injured through excess of temperature. Also, the short, recurrent, shifting, vertical movements of said curtain louvers causes 100 a positive movement downward of the material in contact with and approximate to said louvers. The separation of the material from direct contact with hot wall 12 and the forced downward movement of said material between its outer periphery and chains 47 are the features which this invention adds 105 to that for which said Frank E. Hobson 110 applied for patent as above mentioned.

Having thus disclosed our invention, what we claim as new and desire to secure by Letters Patent is,

1. In a retort comprising a vertical retort shell, a centrally located, vertical gas collector therein and spaced therefrom, means adapted to heat said retort shell, a vertical cylindrical hanging louvered curtain between said gas collector and said shell and proximate to said shell and spaced from said gas collector, and means adapted to shift said curtain vertically whereby material in said retort between said gas collector and said curtain may be prevented from con-

tacting with said shell while being carbonized by heat therefrom and may be caused to move downward in said retort.

2. In a retort comprising a vertical retort shell, a centrally located, vertical gas collector therein and spaced therefrom, means adapted to heat said retort shell, a vertical cylindrical hanging louvered curtain between said gas collector and said shell and proximate to said shell and spaced from said gas collector, spaced chains hanging between said gas collector and said curtain, means adapted to shift said curtain vertically and means adapted to shift said chains vertically whereby material in said retort between said gas collector and said curtain may be prevented from contacting with said shell while being carbonized by heat therefrom and may be stirred while being moved downward in said retort.

3. In a retort in combination, a vertical retort shell, a centrally-located, vertical cylindrical, louvered gas collector within said retort shell and spaced therefrom, means adapted to heat said retort shell, a vertical cylindrical hanging louvered curtain between said gas collector and said shell and proximate to said shell and spaced from said gas collector, spaced chains hanging in said retort between said gas collector and said curtain, means adapted to shift said curtain vertically, means adapted to shift said chains vertically and means adapted to shift said gas collector vertically whereby material in said retort between said gas collector and said curtain may be pre-

vented from contacting with said retort shell while being carbonized by heat therefrom and may be forced to move downward in said retort both at its outer and inner surfaces and within the mass thereof while it is being stirred.

4. In a retort in combination, a vertical retort shell a centrally located vertical cylindrical louvered gas collector within said retort shell and spaced therefrom, a vertical cylindrical hanging louvered curtain between said gas collector and said shell and proximate to said retort shell and spaced from said gas collector, spaced chains hanging between said curtain and said gas collector, controllable means adapted to vertically shift said curtain, said gas collector and said chains through short spaces with intervening periods of pause, means adapted to allow material to enter the top of said retort, controllable means adapted to remove said material from the bottom of said retort, means communicating with and adapted to receive the volatile emanations from said gas collector, and means adapted to control the temperature of said material while in said retort whereby said material may be forced to pass through said retort at a desired rate, may be carbonized by heat from said retort wall without contacting therewith, may be stirred within said retort while passing therethrough and the gaseous emanations therefrom collected.
